UNITED STATES PATENT OFFICE.

SOREN THURSTENSEN, OF LOUISVILLE, KENTUCKY, ASSIGNOR TO HENRY VOGT
MACHINE CO., OF LOUISVILLE, KENTUCKY, A CORPORATION OF KENTUCKY.

WATER-TUBE BOILER.

1,157,737.

Specification of Letters Patent. Patented Oct. 26, 1915.

Application filed July 25, 1914. Serial No. 853,069.

To all whom it may concern:

Be it known that I, SOREN THURSTENSEN, a citizen of the United States, residing at Louisville, in the county of Jefferson and State of Kentucky, have invented certain new and useful Improvements in Water-Tube Boilers, of which the following is a specification.

The present invention relates to a boiler 10 of the well known water tube type, and more particularly to the arrangement of baffles and the location of the steam super-heating drum within the boiler.

The objects of the present invention are 15 to provide a series of baffles so arranged as to cause an efficient circulation of heat around all of the tubes of the boiler; to arrange at one point within the boiler a restricted opening so as to insure a free circulation of the gases about certain of the 20 tubes during their passage through this opening; and to arrange the steam super-heating drum whereby it will be heated sufficient to carry out the purpose thereof, but 25 will be out of direct line of travel of the gases, so that danger of burning out the drum is eliminated.

In the drawings: Figure 1 is a side view of the boiler of the present invention with 30 certain of the parts in section; and Fig. 2 is a section on line 2-2 of Fig. 1, looking in the direction of the arrow.

The boiler illustrated comprises a body 3 of any suitable style and formation having 35 therein the usual grate 4, and communicating with the interior of the body is the usual smoke stack 5. A water drum 6, a mud drum 7, a steam drum 8 and a steam super-heating drum 9 are located within the boiler 40 and supported therein in any suitable manner. A rear set of tubes 10 connect the water drum with the mud drum. A lower set of tubes 11 connect the mud drum with the steam drum, an intermediate set of tubes 45 12 connect the steam with the water drum, and an upper set of tubes 14 connect the steam drum with the super-heating drum, and the super-heating drum with the water drum.

Above the grate 4 is an arch 15, and extending from the said arch rearwardly to a point adjacent the mud drum 7 and below the lowermost of the tubes 11 is a lower baffle 16. Located medially or approximately medially of the set of tubes 11 is an

intermediate baffle 17 extending from the mud drum to a point adjacent the steam drum 8. Both the baffle 16 and the baffle 17 are inclined.

A forward baffle 18 extends from the front 60 of the intermediate baffle 17 to a point above the intermediate set of tubes 12; and a rear baffle 19 extends from the super-heating drum to a point adjacent the top of the tubes 11, and an upper baffle 20 extends 65 rearwardly from the baffle 19 to a point adjacent the tubes 10. The course of the gases is clearly indicated by the arrows in Fig. 1, and, as shown, passes beneath the baffle 16; thence upward, thence forward between the 70 baffles 16 and 17, thence upward again and over the top of the baffle 18, thence downward and between the baffles 17 and 20, thence rearwardly around the tubes 10, and 75 thence upwardly to the smoke stack.

From the foregoing, it is apparent that every part of the tubes of the sets of tubes of the boiler is affected by the circulating gases, and is efficiently acted upon, so that proper results from the combustion of the 80 fuel as respects the generation of steam are obtained. By the use of the arch 15 and baffle 16, a high state of furnace temperature is obtained which insures smokeless combustion, and by the arrangement of the 85 arch and baffle this high furnace temperature is obtained without subjecting the tubes of the lower set 11 to an undue heat which might result in their burning out. It will be noted that the rear baffle 19 terminates 90 very close to the upper of the tubes 11, thus insuring that the gases will pass downward over that portion of the upper of the tubes 11 adjacent the baffle 19.

It will be noted that the super-heating 95 drum 9 is located so that it extends partially into the passage between the vertical baffles 18 and 19 and partially into the passage leading to the smoke stack. By so locating the steam super-heating drum it is taken 100 out of direct line of travel of the gases, so that there is no danger of its being burned out by a subjection to undue heat. At the same time it is located in a position where it is maintained sufficiently hot to perform 105 its function, that is, the super-heating of steam. It is, of course, obvious that a drum of this character could not be subjected to the same temperature as a steam, water, or mud drum without danger of its burning 110

out, since it is, of course, filled only with steam, and the amount of moisture in it is not near so great as in the cases of the other drums mentioned.

5 The drum 6 has been referred to as a water drum and the drum 8 as a steam drum for the sake of avoiding confusion in description. As a matter of fact both the drum 6 and the drum 8 will contain both steam and water and they would both more accurately be referred to as steam and water drums.

I claim:

10 In a boiler the combination of a plurality of drums, an upper, lower, intermediate and rear set of tubes connecting said drums, a lower baffle extending along the bottom of the lower set of tubes to a point adjacent the rear of said tubes, an intermediate baffle

20 lying medially of the lower set of tubes and extending from the rear of said tubes to adjacent the front thereof, a forward baffle extending from the front of the intermediate baffle to a point above the intermediate set of tubes, a rear baffle extending from above 25 the intermediate tubes to a point below said intermediate tubes and extending above and away from the upper tubes of the lower set of tubes, an upper baffle extending from the lower portion of the rear baffle to adjacent 30 the rear set of tubes, and a smoke stack above said upper baffle, substantially as described.

SOREN THURSTENSEN.
